UNITED STATES PATENT OFFICE.

EDGAR H. LUSHER, OF PORTLAND, OREGON.

RAZOR-BLADE HOLDER.

Application filed November 23, 1925. Serial No. 70,812.

This invention relates generally to the tonsorial art, and particularly to means for holding safety razor blades when shaving or while sharpening same or when using same for purposes other than shaving.

The first object of this invention is to provide an exceedingly simple and efficient holder for all kinds of safety razor blades.

The second object is to provide a holder which will be easy to keep clean, easy to manufacture and furnish the maximum amount of support for the razor blade.

The third object is to so construct the blade-engaging end of the holder as to utilize the flexible quality of the wooden portion thereof for the purpose of securing the best possible holding action.

The fourth object is to provide a metal back for the wooden holder for the purpose of preventing warping of the wooden member and the ultimate failure of the holder to properly secure the blade.

These, and other objects, will become more apparent from the specification following as illustrated in the accompanying drawing, in which:

Figure 1 is a side elevation of the device with a relatively long thin blade shown therein. Figure 2 is a bottom view of Figure 1. Figure 3 is a longitudinal section of wooden portion taken along the line 3—3 in Figure 2. Figure 4 is an end elevation of the wooden portion of the holder with the clamp and plate removed therefrom. Figure 5 is an end elevation of the holder showing the metal back in place and holding a wafer blade. Figure 6 is a similar end view showing the metal back on the opposite side and holding a blade of the thicker variety.

Similar numbers of reference refer to the same parts throughout the several views.

Referring in detail to the drawing, the holder itself consists of an elongated wooden handle member 10 whose blade-engaging portion 11 is provided with a narrow slot 12 and a wider slot 13, the sides of which slots are parallel with each other when the members 11 are not under pressure.

The metal back 14 having inturned edges 15 is adapted to slide over the members 11 and compress the nearest edges 16 or 17 according to the manner in which it is placed on the holder.

In Figure 1 is illustrated the long thin

type of blade 18. In Figure 5 is illustrated the relatively short wafer type of blade 19 and in Figure 6 is shown the thick back concave blade 20.

While it will be observed in Figure 4, in which the back 14 is not in place, that the sides of the slots 12 and 13 are parallel, it will be observed in Figures 5 and 6 that under the pressure of the back 14 the halves of the holder, consisting of the members 11, are either rocked on the fulcrums 21 or partially adapt themselves to the shape of the back by the bending of their own structures. In each case it is evident that that portion of the blade which is exposed for cutting purposes is supported rigidly along its cutting edge by the edges 16 or 17, which are reinforced by the metal holder 14.

Attention is drawn to my United States Patent Number 1,534,404 dated April 21st, 1925, over which this device is an improvement.

Owing to the fact that the sanitary feature is greatly improved by eliminating the split handle and that the clamping action is bettered by supporting the blade along its entire length, rather than merely at one end of the holder, and also that it can be more cheaply manufactured and greatly improved in appearance, this device represents an important improvement in the art to which it is related.

The operation of this holder is as follows: When desiring to use same if it is intended to hold a wafer blade the back 14 is removed by slipping same off from the end of the holder and the blade 19 is inserted, as shown in Figure 5, and the back 14 is then slipped over the holder directly behind the blade. If a blade of the type shown in Figure 6 is to be held it is inserted in the slot 13 and the back 14 is applied from the opposite side of the device.

I am aware that many forms of razor blade holders have been constructed in the past: it is therefore not my intention to cover such devices broadly, but I do intend to cover all such forms and modifications thereof as fall fairly within the appended claims.

I claim:

1. A razor blade holder having, in combination, a handle member having a wide slot cut part way through one end thereof; a narrow slot cut through the remainder of said end forming a flexible fork thereon in

a manner that the sides of said fork can be twisted to move toward each other; and a U-shaped longitudinal metal back having its open edges inturned and adapted to compress the nearest edge of said slotted end of the handle member upon a blade held within the nearest slot.

2. A razor blade holder consisting of a handle member having a wide slot formed through one half of one end thereof; a narrow slot through the remaining half of the

same end forming a fulcrum at the junction of said slots; and having an elongated metal back of U-shaped cross section, said back having inturned edges adapted to bear against either edge of said slotted end near the cutting edge of a blade held within either of said slots, said slotted end having sufficient flexibility to permit same to be twisted on their intermediate fulcrum to compress either of its edges.

EDGAR H. LUSHER.
